UNITED STATES PATENT OFFICE.

EMIL B. CARLSON, OF CHICAGO, ILLINOIS.

JAMB-SUPPORTING STAY.

Application filed April 2, 1927. Serial No. 180,434.

My invention is concerned with the provision of certain improvements applicable to jamb supporting stays of the type shown and described in my prior Patent No. 5 1,599,985, dated September 14, 1926.

A jamb stay of the type shown and described in my patent aforesaid is preferably formed in one piece from metal strap and preferably comprises, as its essential 10 elements, an elongated flat body portion and a jamb entering element at one end of and at right angles to the body portion, the jamb entering element being bifurcated to provide a pair of spaced pointed piercing 15 fingers, and the body portion being perforated or otherwise adapted for attachment to a frame or margins of an opening wherein is mounted a door or window jamb engaged by the jamb entering element.

20 A jamb stay embodying my present invention preferably comprises the essential elements in the last paragraph mentioned, and, in addition, is conformed to provide a transverse rib at the junction between the 25 body portion and the jamb entering element, this rib preferably being concavo-convex in cross section, with its convex surface at the exterior of the junction, this rib affording several advantages as will presently appear.

30 In the accompanying drawings, illustrating two embodiments of my invention:

Fig. 1 is a side elevational view, slightly enlarged, of a jamb stay embodying my invention;

Fig. 2 is an end elevational view of the device shown in Fig. 1;

Fig. 3 is a top plan view of the device shown in Figs. 1 and 2.

40 Similar characters of reference refer to similar parts throughout the several views.

Referring, first, to the device shown in Figs. 1 to 3, both inclusive, it will be noted that the jamb stay of my invention is 45 formed from a single piece of metal strap and comprises an elongated flat body portion 10 and a jamb entering element 11, the jamb entering element being disposed at one end of and at right angles to the body portion. The jamb entering element is bifurcated to provide a pair of pointed spaced piercing fingers 12, 12. It will be noted that the piercing fingers are provided with inclined opposed edge portions *a*, *a* which, 50 without meeting, converge toward the body portion 10. The piercing fingers are also

provided with opposed edge portions *b*, *b* which diverge toward the body portion.

The edge portions *a* and *b* of each piercing finger are so disposed that each piercing finger has a pointed shoulder at the junction between its said edge portions *a* and *b*, it being the purpose of these shoulders to engage in and under material embraced between the piercing fingers when 60 the jamb entering element is driven into a door jamb or the like.

The body portion 10 is preferably provided with a plurality of perforations 13, 13 to receive nails or other instrumentalities for attaching the said body portion to a frame, or the margins of an opening, wherein is mounted to a door jamb, or the like which is engaged by the jamb entering 70 element of the stay.

The body portion 10 is preferably provided with means for positioning and indicating the position of the jamb stay with respect to a door jamb or other structure to which the jamb stay is attached, such means 80 preferably taking the form of a stop element 14 which is struck from the metal of the body portion 10, as illustrated in the drawings, and is turned at right angles to the body portion and into parallelism with 85 the piercing fingers of the jamb entering element. The stop element 14 is definitely spaced from the piercing fingers and is somewhat longer than the piercing fingers so that the latter may be accurately positioned 90 in a door jamb or the like by moving the lower end of the stop element against the edge of the jamb into which the piercing fingers are to be driven.

I have not, in the drawings, illustrated 95 the manner of using my improved jamb stay in connection with a door or window jamb because the preferred manner of using jamb stays of this kind is now known, being fully shown and described in my patent 100 aforesaid.

It will be noted that the jamb stay of my present invention is provided with a transverse rib 15 at the junction between the body portion 10 and the jamb entering element 11, 105 this rib being concavo-convex with its convex surface exterior of the angle between the body portion and the jamb entering element and its concave surface interior of such angle.

110 The rib 15 affords several distinctive advantages. It strengthens the stay at the

- junction between the body portion and the jamb entering element. It serves to receive, on its convex surface, the force of the blow of a hammer or other tool utilized in driving the piercing fingers into a jamb or the like and delivers the force of the blow to the piercing fingers much more efficiently and satisfactorily than would be the case were the force of the blow distributed over any considerable area or over any area not substantially behind the points of the piercing fingers. The rib 15 has a further advantage in that its concave surface serves as a recess to receive material which may be displaced when the piercing fingers are driven to position, this being an important consideration when the material into which the piercing fingers are driven is soft wood, plaster, wall-board or other relatively soft material.
- When the jamb entering element is driven into a piece of wood or the like, say for instance a door jamb, the fingers 12, 12 spring apart somewhat, due to the presence of their opposed inclined edge portions α , α , the fingers reacting to clamp the wood or other material between them, and behind their pointed shoulders, when the jamb entering element has been driven to final position.
- The jamb stay is preferably formed with a slot between the prongs, said slot extending upward and backward into the rib or corrugation 15 to divide said corrugation into two independent portions. The bases of the piercing fingers are thus divided and spaced apart where they join the body portion, and the transverse rib is divided into two portions which, in the drawing, have been designated 15^a and 15^b. The rib portions 15^a and 15^b may, if desired, be considered parts of the piercing fingers' bases. When the rib portions are so regarded the piercing fingers properly may be said to extend beyond the body portion 10 on the side thereof which lies away from the points of the piercing fingers.
- The rib portions 15^a and 15^b of the device may be utilized to cause the points of the piercing fingers to be forcibly spread apart to a certain extent by the force of the blow or blows whereby the piercing fingers are driven into a jamb or the like. Thus, when in driving the piercing fingers to position in a piece of wood, the hammer is caused to engage the stay most forcibly at the inner (opposed) ends of the rib portions 15^a and 15^b, the said rib portions will flatten out at their said inner or opposed ends, with the result that the points of the piercing fingers will be spread apart in the wood. This flattening of the inner or opposed ends of the rib portions may be accomplished with an ordinary hammer or a special tool may be utilized for the purpose.
- Having thus illustrated and described two embodiments of my invention, what I claim as new and desire to secure by United States Letters Patent is:
1. A metallic fastener for jambs and the like comprising a stiff metallic main body portion adapted to space a jamb from a supporting member, and having a pair of prongs formed at one end and extending at an angle to said main body portion, said body portion being formed with a transverse corrugation projecting above said main body portion in a direction opposite to the ends of said prongs, forming a recess on the under side of said body portion, and said prongs being separated by a slot dividing said corrugations into two independent portions.
2. A metallic fastener for jambs and the like comprising a stiff metallic main body portion adapted to space a jamb from a supporting member, and having a pair of prongs formed at one end and extending at an angle to said main body portion, said body portion being formed with a transverse corrugation projecting above said main body portion in a direction opposite to the ends of said prongs, forming a recess on the under side of said body portion, and said prongs being separated by a slot dividing said corrugation into two independent portions, and a stop member formed out of a portion of said main body portion extending substantially parallel to said prongs for locating and guiding said prongs and resisting lateral thrust.

In witness whereof, I hereunto subscribe my name this 31st day of March, 1927.

EMIL B. CARLSON.
